(57) **CLAIM**

The ornamental design for a glove with dorsal protection elements, as shown and described.

DESCRIPTION

FIG. 1 is a top rear perspective view of a first embodiment of a glove with dorsal protection elements according to the present design;

FIG. 2 is a right side elevation view thereof;

FIG. 3 is a rear elevation view thereof;

FIG. 4 is a left side elevation view thereof;

FIG. 5 is a front elevation view thereof;

FIG. 6 is a top plan view thereof; and

FIG. 7 is a bottom plan view thereof.

FIG. 8 is a top rear perspective view of a second embodiment of a glove with dorsal protection elements according to the present design;

FIG. 9 is a right side elevation view thereof;

FIG. 10 is a rear elevation view thereof;

FIG. 11 is a left side elevation view thereof;

FIG. 12 is a front elevation view thereof;

FIG. 13 is a top plan view thereof; and

FIG. 14 is a bottom plan view thereof.

FIG. 15 is a top rear perspective view of a third embodiment of a glove with dorsal protection elements according to the present design;

FIG. 16 is a right side elevation view thereof;

FIG. 17 is a rear elevation view thereof;

FIG. 18 is a left side elevation view thereof;

FIG. 19 is a front elevation view thereof;

FIG. 20 is a top plan view thereof; and,

FIG. 21 is a bottom plan view thereof.

The broken lines show portions of the article and form no part of the claimed design.
